LUBRICATING SYSTEM

Application filed April 16, 1928. Serial No. 270,535.

This invention relates to lubricating systems particularly adapted for use in connection with internal combustion engines, and has particular reference to a control means 5 for a lubricating system of this character.

An object of this invention is to provide a lubricating system having means for delivering a special quantity of lubricant to those parts of an internal combustion engine 10 which require special lubrication when the engine is cold, and is just starting into motion.

A further object of this invention is to provide means for delivering the aforesaid 15 special quantity of lubricant, which means will be entirely automatic in its operation.

A still further object of this invention is to provide means for controlling the delivery of a lubricant in dependence upon the 20 temperature of the engine, and in particular, means which will be operable in dependence upon the temperature of a fluid, the temperature of which varies in accordance with the operation of the engine.

25 Other objects and advantages of this invention will become apparent as the following description proceeds, particularly when reference is had to the accompanying drawings wherein:

30 Figure 1 is a semi-diagrammatic plan view of an internal combustion engine showing the invention applied to the same;

Figure 2 is an elevational view of the engine shown in Figure 1; and

35 Figure 3 is a transverse sectional view taken through the structure shown in Figure 1.

In the modern construction of internal combustion engines, particular attention is being directed to the provision of means for 40 eliminating the scuffing of the pistons.

Many tests have been conducted and it has been found that the cause of piston scuffing and excessive wear is due to insufficient or no lubrication when the engine is started cold 45 and that the scuffing can in no way be attributed to small clearance. The wear on the pistons is particularly noticeable when aluminum pistons are used and the modern trend of automobile manufacturers is to use

50 aluminum pistons to a large extent. Further,

the wear does not stop at the pistons and cylinders for it has been found that the lack of initial lubrication is a considerable factor in valve tappet, valve tappet guide and piston pin wear. The present invention contemplates the provision of means to preclude the possibility of this lack of lubrication when starting a cold engine.

Referring now particularly to the drawings wherein like reference characters designate corresponding parts throughout all views, 10 designates the block of an internal combustion engine which block is provided with a plurality of cylinders 11 and the tappet brackets 12 in accordance with the standard practice. Tappets 13 are mounted for reciprocation in the brackets 12, these tappets being adapted to actuate the valves 14 and being themselves actuated by the cams 15. Pistons 16 are mounted for reciprocation in the cylinders 11, these pistons being provided, in accordance with the usual practice, with the annular grooves 17 for receiving piston rings (not shown).

The present invention contemplates the provision of means for feeding a stream of spray of lubricant to the cylinder walls during the initial starting of the engine and while the engine is cold. To accomplish this, there is provided a lubricant chamber 20 adapted to receive lubricant under pressure through a conduit 21 from a suitable source (not shown). In actual practice the lubricant chamber 20 is adapted to be mounted in the force feed lubricating system of the internal combustion engine whereby lubricant under pressure will be supplied to the chamber 20.

As shown, the chamber 20 may be mounted on one side of the block 10 but it is to be clearly understood that this chamber may be mounted at any point on the engine or on the vehicle in which the engine is installed. In fact it might be desirable to mount this chamber 20 on the instrument board along with the other instruments usually located at this point. In any event, however, wherever the chamber 20 is mounted, it is preferable that this chamber be located at a point above the level of the lubricant con-

ducting passages hereinafter to be described.

For supplying a constant flow of lubricant under pressure to the tappets 13, the conduits 22 are provided. As illustrated, these conduits may extend from opposite ends of the chamber 20 and may communicate with passages 23 extending transversely of the block 10, which passages in turn communicate at their ends with passages 24 extending longitudinally of the block 10 and opening into the brackets 12. As illustrated, the passages 24 may be so arranged as to cause the lubricant to flow through each bracket 12 in order to reach the next bracket 15 which is spaced further from the outlet of the passage 23. By this arrangement, a supply of lubricant under pressure will be supplied to the tappets 13 during the operation of the engine.

For conducting lubricant from the chamber 20 to the cylinder walls, a series of conduits may be provided which conduits may preferably be formed as passages within the engine block. Accordingly there is provided within the block 10, a passage 25 which extends longitudinally of the block and which is arranged adjacent the sides of the cylinders 11. The passage 25 is below the level of the chamber 20 and communicates with the chamber 20 by means of a passage 26 which extends upwardly from the passage 25 and outwardly through the side of the block 10 where it opens into the chamber 20. Above the level of the passage 25, each cylinder wall is provided with an aperture 27 and as clearly illustrated in Figure 3 of the drawing, this aperture 27 is preferably located in the cylinder wall at a point opposite the lowermost groove 17 in the piston 16 when the piston is at the end of its down stroke. The apertures 27 are arranged in communication with the passage 25 by means of the short passages 28 which extend upwardly at spaced points from the passage 25 and then laterally to connect with the apertures 27.

As brought out before, the present invention contemplates the provision of means whereby the lubricant will be supplied to the cylinder walls only during the starting of a cold engine. Accordingly the passage 26 at the point where it opens into the chamber 20 is provided with a valve seat 30 adapted to be engaged by a needle valve 31. Obviously when the needle valve 31 seats within the end of the passage 26, the supply of lubricant from the chamber 20 to the passage 25 will be cut off.

For actuating the valve 31 in dependence upon the temperature of the engine, a thermostat 32 is provided, which thermostat may have operative connection with the valve 31 as at 33. The thermostat 32 may be of any desired construction and may be mounted at any point on the engine or on

the vehicle, in which the engine is installed. In the illustrative embodiment disclosed, the thermostat 32 is shown as constituting a bimetallic strip of metal secured to the interior of the chamber 20 as at 34. When 70 the thermostat is located in this position, it will be actuated by the temperature of the lubricant which flows through the chamber 20, and since the temperature of the lubricant varies in dependence upon the 75 temperature of the engine, the thermostat will accordingly be actuated in dependence upon the temperature of the engine.

It is to be clearly understood, however, 80 that the thermostat 32 may be located in any one of a number of different places. For example, the thermostat 32 may be located in the exhaust manifold of the engine so that as the temperature of the exhaust increases, the thermostat will be actuated to move the valve 31. Or again if the engine is cooled by water in accordance with the general practice, the thermostat 32 might be located at any point in the water circulatory system, whereby it will be actuated 90 when the temperature of the water increases to a predetermined degree. Briefly therefor, the thermostat may be located at any point where it will be effected by the temperature of the engine and may be conveniently located at any point where it will be in contact with a fluid, the flow of which is effected by the operation of the engine and the temperature of which varies in dependence upon 95 the temperature of the engine. 100

In any event, wherever the thermostat is located, this thermostat will be so calibrated as to hold the valve 31 open when the engine is cold and to close the valve 31 when the temperature of the engine is raised to a predetermined degree. Therefore, during the starting of the engine, lubricant will be forced from the chamber 20 through the passages 25, 26 and 28 and will be discharged on the cylinder walls. After the engine has been started, and its temperature has increased to the predetermined degree, the thermostat will function to actuate the valve 31 and cut off the supply of lubricant from the chamber 20 to the cylinder walls. 110

By arranging the passage 25 below the apertures 27 and below the chamber 20, this passage 25 will act as a sump and will always be filled with lubricant. When therefore, the engine is being started, it will not be necessary to fill the entire passage 25 before the cylinder walls will be lubricated. This arrangement provides for an instantaneous lubrication of the cylinder walls immediately upon the starting of the engine 125 and will eliminate entirely the wear on the pistons incident to the initial starting of the engine.

From the above, it is believed that the invention will be readily understood. The 130

chamber 20 is adapted to be arranged in communication with the force feed lubricating system of the engine whereby it will be constantly supplied with lubricant under pressure. During the operation of the engine there will be a constant supply of lubricant under pressure through the conduits 22 to the brackets 12 which form the bearings for the tappets 13. Further, during the initial starting of the engine, the valve 31 will be open and lubricant will be supplied to the cylinder walls. When, however, the temperature of the engine increases due to the operation of the engine, the thermostat 32 will function to close the valve 31 to prevent further lubrication of the cylinder walls.

It will thus be seen that the invention provides a simple and efficient means for delivering to the parts requiring it, a special quantity of lubricant when the engine is cold and is just starting into motion. The device will operate automatically in dependence upon the temperature of the engine and may be so set as to cut off the supply of lubricant to the cylinder walls at any temperature desired.

While one form of the invention has been described in considerable detail, it is to be clearly understood that the description is for the purpose of illustration only and is not definitive of the limits of the inventive idea. The right is therefore reserved to make such changes in the details of construction and arrangement of parts as will fall within the purview of the attached claims.

What I claim as my invention is:

1. The combination with an internal combustion engine having cylinders and tappet bearings, of a lubricant chamber adapted to receive a supply of lubricant under pressure, conduits for conducting lubricant from said chamber to said cylinders and said bearings, and a thermostat in said lubricant chamber for controlling the flow of lubricant through one of said conduits.

2. The combination with an internal combustion engine having cylinders and tappet bearings, of a lubricant chamber adapted to receive a supply of lubricant under pressure, conduits for conducting lubricant from said chamber to said bearings, an additional conduit for conducting lubricant from said chamber to said cylinders, and a thermostat in said lubricant chamber for controlling the flow of lubricant from said chamber to said last mentioned conduit.

3. The combination with an engine having a block provided with a plurality of cylinders, the wall of each cylinder being provided with an aperture, of a lubricant passage arranged within the said block, the said passage having branches communicating with the said apertures, a lubricant cham-

ber adapted to receive a supply of lubricant under pressure and adapted to supply the said passage with lubricant, the said lubricant chamber being arranged above the level of the said passage, a valve in the said lubricant chamber, and a thermostat for actuating the said valve in dependence upon the temperature of the lubricant.

4. In combination an engine block having a plurality of cylinders, the wall of each cylinder being provided with an aperture, a lubricant chamber adapted to receive a supply of lubricant under pressure for discharge through the said apertures, a valve for controlling the flow of lubricant from the said chamber to the said apertures, and means for conducting the lubricant from the chamber to the apertures, said means including a passage extending adjacent the said cylinders, the said passage being arranged below the level of the said apertures and the said chamber whereby the said passage will constantly be filled with lubricant irrespective of the position of said valve.

5. In combination, an engine block provided with a cylinder, a piston mounted for reciprocation in the cylinder, the said piston being grooved to receive piston rings and the wall of the cylinder being apertured, a lubricant passage arranged below the aperture in the wall of the cylinder and being provided with a branch communicating with the said aperture, a lubricant chamber adapted to receive a supply of lubricant under pressure, the said chamber being arranged above the level of the said passage and a thermostatically actuated valve controlling the flow of lubricant from said chamber to said passage.

In testimony whereof we affix our signatures.
